UNITED STATES PATENT OFFICE.

HARRY L. BRADLEY, OF MILWAUKEE, WISCONSIN, ASSIGNOR OF ONE-HALF TO
LYNDE BRADLEY, OF MILWAUKEE, WISCONSIN.

LAVATORY.

1,385,604.

Specification of Letters Patent. Patented July 26, 1921.

Application filed May 31, 1919. Serial No. 300,978.

To all whom it may concern:

Be it known that I, HARRY L. BRADLEY, a citizen of the United States, residing at Milwaukee, county of Milwaukee and State of Wisconsin, have invented certain new and useful Improvements in Lavatories, of which the following is a specification.

My invention relates to improvements in lavatories. The general object of this device is to provide an improved lavatory for use primarily in factories, schools and public or other buildings by a number of persons at the same time, which shall be clean, provide a fresh, clean supply of running water to each of the users thereof and avoid the spread of disease and the splashing and waste of water.

It has been the practice heretofore in factories and similar places where a large number of men are employed, to wash either in buckets or troughs, or in some cases, individual wash bowls. All of these devices are open to serious objections which my invention is designed to overcome. Buckets and wash bowls are of necessity used by several men in succession without adequate opportunity or provision for sterilization or cleaning, and if there is any infection in the first user it is apt to spread to the subsequent users. The different forms of troughs are even more open to the same objection in that the contamination from one user spreads throughout the common water supply and contaminates the others.

My device is designed to give a lavatory that is sanitary, is easily cleaned, in which there is a constantly replenishing supply of pure water, and so arranged that each user gets fresh water direct from the supply without contamination from the other users or from the sides or bottom of the receptacle. In designing lavatories of this kind it is important that the fresh water supply be so arranged that none of the water falls back upon itself. If the supply of water in its downward path mingle with the fresh water in its upward path the soap, dirt, and any contamination there may be mingle with and contaminates the pure water supply and also tends to form pockets or eddies which hold the objectionable matter in suspension and prevent the complete and immediate runoff. Furthermore, the water must be so supplied as to be freely and uninterruptedly flowing at an even and de-

terminable height, whereas if it falls back upon itself or the streams cross the flow is made irregular, at times the flow is detained and there is but little water available, and again the pocket seems to break and the water shoots up to great heights, splashing either outside of the receptacle or into the faces of the users thereof.

Referring specifically to the drawings which form a part of this specification, Figure 1 is a vertical section on the line 1—1, Fig. 2, of a lavatory embodying the invention; Fig. 2 is a plan view of the lavatory; Figs. 3 and 4 show modified forms of fountain with means for adjusting or determining the height and the relative rate of flow of the water in the different concentric circles of orifices. Fig. 5 is a side elevation, partly in section on the line 5—5, Fig. 6, showing a modification of the lavatory; and Fig. 6 is a plan view of the same.

In Fig. 1, 1 is the basin or receptacle of the lavatory, 2 is the fountain therein, 3 is the intake piping, 4 is the strainer and drain, waste or outlet piping, 5 is the hand wheel which operates the shut-off valve 6, 7 is the mixer which is connected with the valve 6 and which operates to regulate the temperature of the water or relative proportions of hot and cold water admitted to the lavatory. The intake piping 3 passes upwardly through an enlarged fitting or section of the outlet pipe 4, so that a single opening in the bottom of the receptacle 1 suffices for the connection therewith of the water supply and waste. In operation the valve 6 is first opened so as to admit the amount of water desired, the rate of flow being controlled thereby, and the mixer 7 is then operated to produce the required degree of warmth. The water issues from the orifices in the fountain 2, which is adapted to throw upwardly and outwardly or obliquely therefrom small, thin or fine jets or streams of water in the form of an inverted frustum of a cone, so that when the streams reach the point of their maximum elevation and begin to fall downward they do so outside or clear of the periphery of the fountain 2, thus avoiding any tendency to form pockets or eddies of water. By this means a number of persons may use the lavatory at the same time and each obtain a sanitary flow of running water without contamination from the others and without contamination

from the deposit on the sides and bottom of the lavatory such as forms in lavatories in which water stands when being used for washing. The strainer and waste pipe 4 are of ample size to carry off the water as fast as it falls upon the bottom of the receptacle 1, thus preventing the backing up of any used water therein. The fountain 2 is preferably made in annular form with the center open, as shown in Fig. 2, so as to afford no dead space or surface in or on which dirty water and germs can accumulate. It is often convenient to have the sides of the basin or receptacle 1 flaring, in which case the hand wheel 5 is connected with the valve 6 by means of a universal joint as shown at 8.

In the fountain 2 as shown there are two annular series of orifices concentrically arranged producing two concentric or parallel series of streams of water. It is desirable that these streams of water do not cross or intermingle before reaching the point of maximum elevation and to this end I provide means for adjusting or determining the relative heights of the respective streams. This may be done either by varying the size, shape, or angle of the respective series of orifices as shown in Fig. 1; by providing separate water supplies to each of the annular spaces 9 with a separate cock or adjusting means 10 for regulating the relative rate of flow thereto as shown in Fig. 3; or the inside set of orifices may be elevated sufficiently above the outside set of orifices to produce this result as shown in Fig. 4. In the drawing two sets of orifices only are shown, but the device can operate with either one set or with three or more. I do not limit myself to the use of two.

In designing the receptacle 1, it may, if desired, be made as shown in Figs. 5 and 6 by using a pan or basin 1' or similar device at the bottom for catching the water and surrounding it with a curtain or splash shield 11 supported on a circular rod 12. In any event the portion of the device that rests upon the floor should be made as shown, to afford a recess into which the users' feet can extend. It is also important that the edge of the lavatory or the rod 12 supporting the shield, if that form is used, be of sufficient height and strength to afford a support or rest for users; so that in leaning over the lavatory the knees or other parts of the bodies of users may rest thereon and prevent them from accidentally being precipitated into the lavatory. If desired soap dishes may be hung on the edge of the lavatory on the inside thereof so that the water therefrom will drain into the lavatory and out through the drain pipe 4.

Having fully described my invention, I claim:

65 1. In a lavatory the combination of a re-

ceptacle provided with a waste outlet leading from the lower part thereof, and a fountain located within said receptacle and provided with a water supply connection and adapted to project upwardly and obliquely a plurality of closely associated non-interfering fine streams of water and to cause them to fall inertly, clear of the fountain, into the receptacle, without the falling streams mixing with the upwardly projected streams.

2. In a lavatory the combination of a receptacle provided with a waste outlet leading from the lower part thereof, and a fountain located centrally within said receptacle and provided with a water supply connection and with jet orifices adapted to project upwardly and outwardly parallel series of closely associated non-interfering fine streams of water and to cause them to fall inertly clear of the fountain into the receptacle between the fountain and the margin of the receptacle without the falling streams mixing with the upwardly projected streams.

3. In a lavatory the combination of a receptacle provided with a waste outlet, a fountain located within the receptacle and provided with a water supply connection and with jet orifices adapted to project upwardly and obliquely parallel series of closely associated fine streams of water and to cause them to fall inertly into the receptacle clear of the fountain, and means for determining the relative altitude to which the streams of different series are projected from the fountain.

4. In a lavatory the combination of a receptacle provided with a waste outlet and formed to receive beneath it the feet of users, and a fountain located within the receptacle and adapted to project upwardly and outwardly from the fountain a plurality of non-interfering fine streams of water and to cause them to fall inertly clear of the fountain into the receptacle between the fountain and the margin of the receptacle without the falling streams mixing with the upwardly projected streams.

5. In a lavatory the combination of a receptacle provided with a waste outlet and above the base with a rest for users, and a fountain provided with a water supply connection and adapted to project upwardly and outwardly therefrom a plurality of closely associated fine streams of water and to cause them to fall inertly into the receptacle between and clear of the fountain and the margin of the receptacle adjacent said rest.

6. In a lavatory the combination of a receptacle having an inwardly recessed supporting base adapted to rest on a floor and to receive the feet of users and provided with a waste outlet and above the base with a rest for users, and an annular fountain

centrally located in said receptacle and provided with a water supply connection and with jet orifices adapted to project upwardly and outwardly therefrom a series of fine streams of water and to cause them to fall inertly into the receptacle between and clear of the fountain and the margin of the receptacle adjacent said rest.

7. In a lavatory the combination of a receptacle provided with a waste outlet leading therefrom and a fountain provided with a water supply connection and adapted to

project upwardly a plurality of non-interfering fine streams of water and cause them to fall in close association with one another 15 inertly into the receptacle clear of the fountain and of the ascending streams without the falling streams mixing with the upwardly projected streams.
